(57) **CLAIM**

The ornamental design for a hand luggage with horizontal cinching straps, as shown and described.

DESCRIPTION

FIG. 1 is a front perspective view of a first embodiment of the hand luggage with horizontal cinching straps embodying my new design.

FIG. 2 is a rear view of the hand luggage with horizontal cinching straps shown in FIG. 1.

FIG. 3 is a right end view thereof.

FIG. 4 is left end view thereof.

FIG. 5 is a top view thereof.

FIG. 6 is a bottom view thereof.

FIG. 7 is a front perspective view of a second embodiment of the hand luggage with horizontal cinching straps embodying my new design.

FIG. 8 is a rear view of the hand luggage with horizontal cinching straps shown in FIG. 7.

FIG. 9 is a right end view thereof.

FIG. 10 is a left end view thereof.

FIG. 11 is a top view thereof; and,

FIG. 12 is a bottom plan view thereof.
